E. H. KRUSE.
LATH STAY,
APPLICATION FILED DEC. 5, 1916.

1,258,916.

Patented Mar. 12, 1918.

UNITED STATES PATENT OFFICE.

EDWARD H. KRUSE, OF FORT WAYNE, INDIANA.

LATH-STAY.

1,258,916.

Specification of Letters Patent. Patented Mar. 12, 1918.

Application filed December 5, 1916. Serial No. 135,123.

To all whom it may concern:

Be it known that I, EDWARD H. KRUSE, a citizen of the United States of America, and resident of Fort Wayne, in the county of Allen and State of Indiana, have invented 5 certain new and useful Improvements in Lath-Stays, of which the following is a specification.

This invention relates to improvements in 10 lath stays intended especially to be used in conjunction with mounting strips for electrical switch-boxes such, for example, as those disclosed in my application for Letters Patent, Sr. No. 78,854.

15 The object of the improvement is to afford support for the extending ends of lath which terminate adjacent the switch-box which in some instances is placed in position between the studding to which the lath are 20 secured and beyond which the lath extend, the present invention being intended to secure the extending ends of the lath adjacent the switch-box that is placed between the studding.

25 The object of the invention is accomplished by the construction illustrated in the accompanying drawing, in which:

Figure 1 is a perspective view showing a switch-box supported in mounting strips, 30 and also the invention applied in conjunction with the mounting strips for securing the ends of the adjacent lath;

Fig. 2 is a side elevation of the support; and.

35 Fig. 3 is a front elevation of the same.

Similar characters of reference indicate corresponding parts throughout the several views and referring now to the same:

A is the support, made of sheet metal, and 40 having flat end portions (B) adapted to be introduced and held within the U-shaped mounting strips (C) by extending thereinto. The metallic plate forming the support has rearwardly and forwardly bent 45 portions, (D) and (E) respectively, the plate being split vertically from a point near one end thereof to a corresponding point near the opposite end thereof, and the two portions being pressed from the general plane

of the plate so as to extend in parallel planes 50 that are spaced apart. The space between said portions are made to correspond approximately with the thickness of lath so that the projecting ends of the lath may be introduced between the rearward and forward 55 portions of the support. In the rearward and forward portions of the plate are made indentations (F) located approximately at their middles, the indentations being intended to hold the lath apart from 60 each other while secured in the support.

In Fig. 1 is illustrated the mounting strips (C) that support a receptacle (G) of known construction that is adapted for the reception of an electrical switch, the latter not being shown. The lath (H), secured to the studding (J) extend to a point adjacent the receptacle (G) with their ends projecting into the support (A), the latter being positioned with its ends (B) extending respectively into the mounting strips (C). When the ends of the lath are thus held, and the wall is completed in the customary manner by applying superficial coats of plastering, a substantial wall construction is obtained even though the lath are cut to admit of the introduction of the switch-box.

What I claim is:—

In a device of the class described, the combination of a pair of oppositely positioned U-shaped strips, and a lath support, the flat end portions of which are adapted to be inserted respectively into the U-shaped strips and held thereby, the support having intermediate transverse members spaced apart by the rearward and forward respective portions thereof and adapted to receive and support therebetween the projecting ends of lath, said support being also adapted to be 90 adjustably shifted in position from one end of said strips to the other.

In testimony whereof I affix my signature, in presence of two witnesses.

EDWARD H. KRUSE.

Witnesses:

MARIE A. HARTMAN,
MATILDA M. METTLER.
